JOHN VAN NOSTRAND DORR, OF DENVER, COLORADO.

AGITATOR.

1,131,222.

Specification of Letters Patent.

Patented Mar. 9, 1915.

Application filed July 29, 1911. Serial No. 641,244.

To all whom it may concern:

Be it known that I, JOHN V. N. DORR, a citizen of the United States of America, residing at Denver, in the county of Denver 5 and State of Colorado, have invented certain new and useful Improvements in Agitators, of which the following is a specification.

My invention relates to agitators for use 10 in the treatment of ores, and more particularly to apparatus of the type employed in the treatment of finely ground ores by cyanid of potassium and other solvents, to bring the material into intimate association 15 with the cyanid solution.

The object of the present invention resides in the provision of an apparatus of 20 simple construction which at a comparatively low cost of installation and operation, will effect and maintain a thorough intermixture of the ore and solvent; which in its operation provides for the proper aeration of the material under treatment; which is adjustable to vary the period of 25 agitation for different sized particles of ores, and will agitate the pulp at any selected degree of density; which is automatic and continuous in its action and, in which the process of solution is materially expedited by a scouring and washing action 30 upon the solid constituents of the pulp.

With the above enumerated objects in view, I provide a circular tank of any convenient size in which an upright, hollow, 35 open-ended conduit is rotatably suspended from a superposed bearing. This conduit carries at its lower extremity two or more radial arms, each provided with a series of obliquely arranged scraper-blades.

40 The arms which are pivotally connected with the conduit, extend in upwardly and outwardly inclined lines for the purpose of conducting the subsiding material along the flat bottom surface of the tank toward 45 a central point below the lower open end of the conduit whose longitudinal axis is coincident with that of the tank. The thickened matter thus continuously conducted toward the orifice of the conduit is drawn 50 upwardly there-through by the action of what is commonly known as an "air lift," which causes the matter to rise by the introduction of air under compression into

the conduit. The elevated material overflows the upper edge of the conduit into a 55 surrounding hopper whence it flows into two or more radially extending, downwardly inclined troughs or launders which distribute it uniformly over the surface of the pulp contained in the tank, through 60 openings in their bottoms. Slanting aprons, adjustably arranged below or above the openings in the troughs, are provided to regulate the size thereof for the purpose of classifying the discharge in accordance with 65 the size of its solid particles and distributing the pulp uniformly over the surface of the liquid. The ore is fed into the tank at one side thereof through a pipe near its upper edge, and the pulp is discharged at 70 its opposite side through a conduit disposed substantially at the same elevation as the inlet pipe. It is obvious that if so desired, a plurality of the agitators may be arranged in series so that matter discharged from one 75 is received into the next succeeding one. An adjustable device of simple construction is provided to regulate the density at which the pulp is discharged from the tank. This device consists of a vertically adjustable 80 baffle plate of curved section which is placed over the opening to provide an upright flue which receives the pulp at its lower end and conducts it to the discharge pipe. A shield flaring outwardly from the lower end of the 85 baffle plate is provided to restrain a percentage of the coarser particles of the pulp from entering the same.

It will be readily understood that by proper adjustment of the lower end of the 90 baffle relative to the discharge opening in the tank, the pulp may be drawn from the tank at any desired level whereby the proportion of solids to liquid that is retained in the tank is effectively regulated, and 95 when equilibrium is reached the pulp is discharged from the agitator at the same density at which it was introduced thereto, but is agitated at a different density.

From the above description it will be observed that the agitator when properly adjusted, is automatic and continuous in its action and inasmuch as the heavier constituents of the pulp subside with greater rapidity than the lighter particles, it follows that the frequency of the circulatory 100 105

movements of the various particles through the conduit and the surrounding fluid, varies in accordance to their size and weight, thus giving the coarser particles the values 5 of which are more difficult to recover, more active agitation.

The slowly revolving scraper arms not only convey the pulp to the orifice of the upright conduit, but also assist in the dissolution 10 of the soluble constituents by so advancing the sandy particles that they rub on each other and so remove any coating of colloidal slime that may interfere with the penetration and diffusion of the solution.

15 It is a well established fact that for the purpose of effecting solution in the treatment of ores heretofore referred to, the agitating action upon the material under treatment should not result in a movement 20 of the entire mass, but rather cause independent movements of the solid particles through the solvent so as to bring them constantly in contact with fresh portions thereof.

25 The advantages of my improved agitator over other well-known methods may be readily understood.

In air agitation alone it is usual to have great height compared to depth, to slope 30 the bottom into a cone and especially with a reground product to use enough air to cause violent circulation in order to avoid building upon the cone, thus requiring much more power than would otherwise be 35 necessary and using an excess of air which would consume cyanid, etc. The former objection *i. e.* excessive power, applies also to screw agitators. With mechanical arm agitators which usually operate in the bottom 40 of a tank, it is found that a violent agitation is required at the bottom in order to produce enough agitation at the top, and if aeration is required that must be added.

In my agitator which combines the good 45 points of mechanical and air agitation, a slow operation of the plow arms induces a slow motion of the whole pulp and prevents any accumulation of thickened material on the bottom. The air lift insures the aeration 50 of all the pulp and solution as often as necessary, and its complete change of position, but allows the regulation of the power to accomplish the extraction at minimum cost with no necessity of use of additional 55 power for mechanical reasons only. Compared with centrifugal pump agitation there are no wearing parts and the agitation is uniform all over, while the power is a small fraction of that required. With 60 granular material the lifting of the thick pulp and dropping it through the solution is a great saving over circulating the whole mass and gives the maximum relative motion between solids and liquid.

The advantageous features of my invention 65 set forth in the above description, are of particular importance in the modern method of treating reground sand and slime together which, while simplifying the operation and construction of the mill, introduces both mechanical and chemical difficulties not found in the separate treatment 70 of the sand and the slime as was practised in the earlier period of the cyanid process.

The selective feature of my invention 75 whereby only the thickened pulp is moved, naturally reduces the cost of operation, for while for example, it would require a lifting of four parts of mixture, by weight, for each part of solids in a three to one pulp, 80 only a lifting of two parts of the mixture will be necessary to move the same amounts of solids in a one to one pulp.

An embodiment of my invention is illustrated in the accompanying drawings in the 85 various views of which like parts are similarly designated, and in which—

Figure 1 represents a central, vertical section through the apparatus; Fig. 2, a transverse section taken along the line 2—2, Fig. 90 1, Fig. 3, a similar section along the line 3—3 Fig. 1, and, Fig. 4, a sectional, perspective view of a portion of one of the distributing troughs, showing the construction 95 of the discharge openings in the bottom thereof.

The reference character 2 designates the cylindrical tank, and 3 the upright conduit which is rotatably suspended therein from a bearing 4, by means of a hollow shaft 5 100 which extending within its upper portion, is rigidly connected therewith by means of a number of lugs 6. The shaft 5 is provided at its upper extremity with a worm wheel 7 which meshes with a worm 8 upon 105 a shaft 9 which may be connected with any suitable source of power.

The radial arms 10 which carry the series 110 of obliquely arranged scraper blades 12, are pivotally attached at the lower end of the conduit 3 and they are adjustably suspended in an upwardly and outwardly inclined position by means of rods 13, which at their upper ends are connected with a collar 14 which is vertically slidably connected with the conduit. The upper extremity of the conduit 3, which projects 115 above the level of fluid in the tank, carries the surrounding hopper 15 which communicates with the downwardly directed, radial 120 distributing troughs 16. The discharge openings 17 in the bottoms of these troughs are formed by cutting the latter along three edges of a rectangle and bending the included portion 18 up or downwardly along 125 the fourth edge of the same. By bending the aprons thus formed, to different angles, the size of the material discharged through

the respective openings may be readily regulated to suit varying circumstances and conditions.

The material to be treated is introduced 5 into the tank through a conduit 19 at the upper portion thereof, and the pulp is discharged therefrom by means of a conduit 20 which connects with an orifice formed substantially on a level with the inlet.

10 The egress orifice is covered by the baffle 21 which is vertically slidably mounted in guideways 22 upon the inner surface of the tank, and which terminates at its lower extremity in an outwardly flaring shield 15 23, the function of which has been hereinbefore explained.

The air required to lift the thickened material through the hollow column 3, into the surrounding hopper, is introduced into the 20 column through a series of small apertures formed at the lower end of a pipe 24 which extends axially through the conduit and the therewith connected shaft 5, to connect at its upper extremity with a source of air under 25 compression.

As the operation of my apparatus has been referred to at intervals in the course of the foregoing description, it will only be necessary to describe it very briefly at this 30 point. The material to be treated is fed through the pipe 19 into the tank 2 where it joins the pulp already contained therein, in its circulatory movement from the surface downwardly toward the orifice at the lower 35 end of the conduit 3 and thence upwardly through the latter by the action of the air lift, to be distributed uniformly over the surface of the pulp through the openings in the troughs 16. In the above described 40 movement, the solids which gradually settle in the tank, are conveyed toward the orifice of the conduit by the action of the scrapers 12 on the rotating arms 10, and the sand which settles faster than the colloidal matter 45 is in consequence, drawn most frequently through the air-lift.

The pulp is discharged from the tank through the upright flue formed by the baffle 21, and the therewith communicating 50 conduit 20, and inasmuch as the density of the matter contained in the tank must necessarily vary in ratio to its depth, the density of the discharged pulp may be readily determined by varying the elevation of the 55 lower end of the baffle, the shield 23 restraining the coarser particles contained in the pulp as hereinbefore explained.

Having thus described my invention what I claim and desire to secure by Letters- 60 Patent is:—

1. An agitator comprising a vessel, an upright conduit having an ingress-opening near the bottom thereof, and an egress opening at its opposite end, means for conveying

subsiding matter toward the said ingress- 65 opening, means adapted to raise the said matter within the conduit to its egress-opening, and a launder disposed to receive matter discharged through the latter, and provided with openings for the distribution of 70 said matter over the surface of material contained in the vessel and with adjustable aprons extending obliquely relative to the said openings.

2. An agitator comprising a vessel, an upright rotary conduit having an ingress opening near the bottom thereof and an egress opening at its opposite end, outwardly extending arms at the lower end of the conduit, having obliquely arranged scraper blades, 75 and adapted to be raised to a vertical position, means for raising matter conveyed to the ingress-opening, to the egress-opening of the conduit, means for distributing matter discharged through the latter uniformly 80 over the surface of material contained in the vessel, according to the size of its particles, and a vertically adjustable, upright flue having at its lower end an inlet within the vessel. 90

3. In an agitator, a vessel having a substantially flat bottom, means for effecting a continuous movement of matter from a point near the said bottom to a point adjacent the surface of material contained in the vessel, 95 and mechanical means for conveying subsided matter toward the first-mentioned point.

4. In an agitator, a trough having discharge openings, and adjustable aprons extending obliquely relative to said openings. 100

5. In an agitator, a trough having discharge openings and integral aprons extending obliquely beneath said openings.

6. In an agitator, a vessel, means for 105 raising subsiding matter from a point near the bottom thereof, and a device for the distribution of said raised matter in said vessel, provided with openings at different distances from the center of the vessel and 110 with means to separately vary the sizes of said openings.

7. In an agitator, a vessel, a rotary conduit having an ingress opening near the bottom thereof, and an egress opening at its 115 opposite end, means for the introduction of air into said conduit, and means connected with said conduit to convey by its rotary movement, subsided matter toward the ingress-opening thereof. 120

8. In an agitator, a vessel, a rotary conduit having an ingress opening near the bottom thereof, and an egress opening at its opposite end, means for the introduction of air into said conduit, means connected with 125 said conduit to convey by its rotary movement, subsided matter toward the ingress-opening thereof, and a device connected with

said conduit to receive matter discharged through its egress opening and to distribute the same by its rotary movement, in the said vessel.

5. 9. In an agitator, a vessel having an outlet, and a flue in communication with said outlet and having an inlet within the said vessel, said flue being adjustable to vary the distance of its inlet to the bottom of the 10 vessel.

10. In an agitator, a vessel having an outlet, means for raising matter from a point near the bottom of said vessel, means for conveying subsiding matter toward said

15 point, and adjustable means for conducting matter from a selected depth of said vessel, to the said outlet.

11. In an agitator, a trough having discharge openings, and aprons extending 20 obliquely below the same, said aprons being bendable to vary the distance between them and the part of the conduit in which said openings are formed.

12. In an agitator, a vessel, a rotary upright conduit having an ingress opening near the bottom thereof and an egress opening 25 at its opposite end, means connected with said conduit for effecting by its rotary motion, a flow of material adjacent said bottom, toward said ingress opening, and means for raising matter in the conduit to the egress opening thereof.

13. In an agitator, a vessel, a rotary upright conduit having an ingress opening 35 near the bottom thereof and an egress opening at its opposite end, means connected with said conduit for effecting by its rotary motion, a flow of material adjacent said bottom, toward said ingress opening, means for 40 raising matter in the conduit to the egress opening thereof, and means connected with the conduit for distributing by its rotary movement, said raised matter in the said vessel.

45. 14. In an agitator, a vessel, an upright conduit having an ingress opening near the bottom thereof and an egress opening at its opposite end, a pipe for the introduction of air into said conduit whereby to raise loose 50 material from the bottom of the vessel in the said conduit to the egress opening of the same, and mechanical means for preventing material subsiding toward said bottom from assuming a solid state, thereby 55 causing the same to flow toward the said ingress opening to replace matter raised in the conduit.

60. 15. In an agitator, a vessel, a rotary upright conduit having an ingress opening near the bottom thereof and an egress opening at its opposite end, a pipe for the introduction of air into the said conduit whereby to raise loose material from the bottom of the vessel in the conduit to the egress open-

65 ing of the same, and mechanical means connected with said conduit for preventing by its rotary movement, material adjacent the bottom of the vessel from assuming a solid state, thereby causing the same to flow toward said ingress opening to replace matter 70 raised in the conduit.

16. In an agitator, a vessel, means for raising matter from a point near the bottom thereof, and a rotary device adapted to discharge said raised matter in said vessel 75 at different points from its axis of rotation in accordance with the sizes of particles contained in said matter.

17. In an agitator, a vessel, an upright conduit having an ingress opening near the 80 bottom thereof and an egress opening at its opposite end, means for raising loose material from the bottom of the said vessel, in the said conduit to the egress opening of the same, and mechanical means for preventing material subsiding toward said bottom from assuming a solid state, thereby 85 causing the same to flow toward the said ingress opening to replace matter raised in the conduit.

18. In an agitator, a vessel, means for raising subsiding matter from a point near the bottom thereof, and a rotary device having means for distributing said raised matter uniformly over the entire surface of material contained in said vessel.

19. In an agitator, a vessel, an upright conduit rotatably suspended within said tank, with its open lower end in spaced relation to the bottom of the same, means 100 above the tank for the rotation of said conduit, a contrivance connected at the lower end of said conduit for effecting by rotation of the latter a flow of material toward the opening at its said end, and means for raising matter in said conduit to a point of discharge at its upper end.

20. In an agitator, a vessel, an upright conduit rotatably suspended within said tank, with its open lower end in spaced relation to the bottom of the same, means 110 above the tank for the rotation of said conduit, a contrivance connected at the lower end of said conduit for effecting by rotation of the latter a flow of material toward the 115 opening at its said end, means for raising matter in said conduit to a point of discharge at its upper end, and means connected with the conduit for receiving matter thus discharged therefrom and distributing 120 the same in the said vessel.

21. In an agitator, a vessel, a rotary, upright, open-ended conduit suspended therein in spaced relation to its bottom, means at the upper end of the conduit for distributing material discharged through said end, in the vessel, means connected with said conduit for effecting by its rotary motion, a

flow of material adjacent said bottom toward the lower end of the conduit, and a stationary air-supply pipe extending through the upper end of the conduit, to a
5 point adjacent the lower extremity of the same.

In testimony whereof I have affixed my signature in presence of two witnesses.
